[57] CLAIM

The ornamental design for a cosmetic container, as shown and described.

DESCRIPTION

FIG. 1 is a front elevational view of a cosmetic container showing my new design; the rear view being a mirror image of FIG. 1.

FIG. 2 is a right side elevational view thereof; the left side elevational view being a mirror image of FIG. 2.

FIG. 3 is a top plan view thereof.

FIG. 4 is a bottom plan view thereof.
